D. R. Throop

BY

Perry J. Webster

ATTORNEY

UNITED STATES PATENT OFFICE.

DAMON R. THROOP, OF STOCKTON, CALIFORNIA.

SCRAPER.

Application filed November 3, 1925. Serial No. 66,438.

This invention relates to improvements in scrapers and particularly represents an improvement over that type of scraper shown in my Patent No. 1,464,687, dated August 14th, 1923.

In this former device a fundamental feature was the arrangement of parts which caused the forward movement of the bowl to aid in enabling the means normally holding the same, to be easily released.

In this device however the movements of the bowl relative to its supporting frame were all controlled by a single member. This structure was slow in operation and did not permit a setting of the scraper blade for different scraping depths which could be maintained undisturbed regardless of the number of dumping operations.

The principal object of the present invention is to provide a scraper which while retaining the above valuable fundamental feature, is much quicker in operation, has means for setting the blade to scrape at any desired depth, and additional means for enabling the bowl to be instantly upset without interfering with or disturbing the setting of the first named means in any way.

The scraper bowl after being turned to a spreading or dumping position, may therefore be returned to its normal scraping position with the assurance that the blade will then be positioned at the same scraping depth or angle as before.

The present device is also much less expensive to manufacture.

These objects I accomplish by means of such structure and relative arrangement of parts as will fully appear by a perusal of the following specification and claims.

In the drawings similar characters of reference indicate corresponding parts in the several views:

Fig. 1 is a perspective view of the scraper in its scraping position.

Fig. 2 is a fragmentary side elevation with the parts in the same position as in Fig. 1, partly broken out to show a catch feature.

Fig. 3 is a fragmentary side elevation, showing the catch released and the bowl turning to a dumping position.

Referring now more particularly to the characters of reference on the drawings, the numeral 1 denotes the side frames of the scraper, which are parallel at their rear ends and converged to a junction with each other

at their forward ends, at which ends they are provided with a clevis 2 for attachment to a tractor. A central longitudinal frame member 3 is mounted intermediate the frames 1 and is connected at its rear end to a transverse beam 4 which is disposed some distance ahead of the rear ends of the frame 1.

Disposed between the frames 1 to the rear of the beam 4 is a scraper bowl 5 of standard "Fresno" form, pivotally mounted on said frames by trunnions 6. Curved shoes 7, such as are ordinarily provided on scrapers of this character extend upwardly from the sides of the bowl from the front to the rear ends thereof.

Turnably mounted on the frames 1 ahead of the bowl is a transverse shaft 8. From each end of the shaft a horizontal arm 9 extends rearwardly on the outside of the bowl, and is adapted to normally extend under a pin 10 projecting outwardly from the forward side of the adjacent shoe 7. Another pin 11 concentric with the pin 10 with respect to the trunnions 6 is adjustably mounted on the shoe a certain distance rearwardly of the pin 10. Pivoted on a bracket 12 mounted on the central beam 3 ahead of the shaft 8, is a longitudinally extending lever 13, which projects forwardly to a point adjacent the forward end of the scraper frame. An ordinary form of quadrant and pawl structure indicated at 14 is associated with this lever so that it may be maintained immovable at any position desired.

Projecting upwardly from the rear and pivoted end of the lever is a forked arm 15. A horizontal link 16 is slidably mounted in this arm, the rear end of this link being pivoted onto a vertical arm 17 which projects upwardly from and is fixed on the shaft 8.

A transverse pin 18 projects through the arm 15 under the link, and normally seats in the forward end of a catch notch 19 cut in the side of said link.

A tension spring 20 between the forward end of the link and the frame 3 acts to normally hold said notch in driving engagement with the pin 18. Another tension spring 21 between the frame 3 and the arm 17 acts to pull said arm forward, and consequently tends to raise the arms 9.

It will therefore be seen that when the lever 13 is moved up or down, the arms 9

- are similarly moved, causing the position of the pins 10 to be altered, and consequently altering the angle of setting of the scraper bowl relative to the frame. This operation 5 controls the normal setting of the scraper bowl. When raising the arms 9 and tilting the bowl upwardly by this manipulation of the lever, the spring 21 aids this operation, offsetting the resistance of the bowl. When 10 moving the lever in the opposite direction, the spring is placed in tension, but the bowl offers no resistance, since the arms 9 move away from the pins 10. When the bowl is pulled forward by the forward movement 15 of the frame, the bowl tends to rotate and tilt downwardly, causing the pins 10 to follow up and reengage the arms 9, thus causing the scraper blade to be set to work at a predetermined angle.
- 20 To enable the bowl to dump automatically with the forward movement of the frame, without touching the lever, or disturbing any setting of the same which may have been made, I provide the following 25 trip structure:

Pivoted at one end onto the pin 18 is a downwardly depending arm 22, the upper portion of which is at an angle to the lower portion, such that the arm is substantially 30 in the form of an inverted L.

The lower end of this arm is attached to a pull cable 23 or the like, which extends forwardly to a point where it may be manipulated by the operator of the tractor 35 hauling the scraper.

At the junction of the angled portions of the arm 22 is mounted a transverse member preferably in the form of a roller 24, this member being under and in the vertical 40 plane of the link 16 but normally clear of the same, as shown in Figs. 1 and 2.

The shape of the arm is such that it normally hangs in this position without the aid of springs etc.

45 Since the arm is mounted in direct connection with the arm 15 of the lever 13, it always follows up any movement of such arm and lever, the cable 23 normally lying sufficiently slack to enable said arm 22 to maintain its neutral position.

When the cable 23 is pulled, the lower end of the arm 22 is moved forward, and the upper portion is moved upwardly as shown in Fig. 3. This causes the member 55 24 to engage and raise the link, so that the notch 19 clears the pin 18.

Since with the forward movement of the bowl the pins 10 constantly press on the arms 9, this releasing of the link from the lever 13 which is held immovable enables said arm 9 to tilt down so that the pins 10 can pass by the same and allow the bowl to upset.

If the cable is then released the arm 22 65 immediately returns to its normal position.

As soon as the pins 10 pass by the arms 9 the latter, together with the link, are restored to their normal positions by the action of the spring 21, which also causes the link notch to be again moved into 70 engagement with the catch pin 18. When the pins 11 then approach the arms 9, said pins will engage the arms and the bowl will be held from further upsetting movement. This position of the bowl allows a spreading discharge of the material therein to be 75 had.

If it is desired that the bowl shall completely upset so as to dump its load all at once, the pulling pressure on the cable 23 is 80 maintained, so that the member 24 is held raised and the notch in the link cannot re-engage the pin 18. Then when the pins 11 reach the arms 9, they can depress and pass by said arms, of course permitting un- 85 restricted upsetting movement of the bowl.

From the foregoing description it will be readily seen that I have produced such a device as substantially fulfills the objects 90 of the invention as set forth herein.

While this specification sets forth in detail the present and preferred construction of the device, still in practice such deviations from such detail may be resorted to as do not form a departure from the 95 spirit of the invention, as defined by the appended claims.

Having thus described my invention what I claim as new and useful and desire to secure by Letters Patent is:

1. A scraper including a pivotally mounted bowl, means including an adjustable lever for controlling the scraping position of the bowl, and means independent of the lever but releasably connected therewith to 100 normally prevent rotation of the bowl, but which, upon being released from engagement with the lever, will allow the bowl to rotate independently of the set position fixed by the lever.

2. A scraper including a pivotally mounted bowl, an adjustable lever, a link releasably connected thereto and normally movable therewith, means between the link and bowl to hold the latter in scraping position 105 when the link is connected to the lever, and means for releasing the link from the lever whereupon the bowl will be free to move on its pivot to dumping position.

3. A scraper including a frame, a bowl 120 pivotally mounted thereon, an adjustable lever, a link releasably connected thereto, and normally movable therewith, release means for the link mounted on the lever, and means between the link and bowl 125 whereby the scraping position of the bowl is controlled by movement of the link with the lever while the bowl is free to move to a dumping position when the link is released.

4. A scraper including a frame, a bowl 130

pivots mounted thereon, an adjustable lever, a link releasably connected thereto, and normally movable therewith, means between the link and bowl whereby the bowl may be adjustably positioned and is held immovable relative to the frame when the link is connected to the lever and is free to move to a dumping position when said link is released, and means for releasing the link operable irrespective of the setting of the lever and link.

5. A scraper including a pivotally mounted bowl, a projecting stop pin on the bowl ahead of its pivotal connection with the frame, a pivoted arm normally projecting under and engaging the pin, and adjustable means including a hand operated lever separate from but releasably connected with the arm for normally holding said arm rigid but permitting of its controlled movement about its pivot when released from the lever.

6. A structure as in claim 5, in which means, operating independent of the lever, is provided for freeing said arm to enable the rotative tendency of the bowl had with the forward movement of the frame to cause the pin to depress and move past the arm.

7. A scraper including a frame, a bowl pivotally mounted thereon, an adjustable lever, a pin projecting from the bowl parallel to and ahead of its pivotal connection with the frame, an arm normally projecting under and engaging the pin, a shaft turnably mounted in the frame and on which said arm is fixed, another arm projecting from and affixed to said shaft, a link extending from said other arm, releasable catch means between the link and lever normally holding the two in driving engagement, and a trip structure operable at will for releasing the link from the lever.

8. A structure as in claim 7, in which means is provided for enabling the lever to be maintained immovable in any position, and spring means acts on the link to tend to maintain the same in engaged relationship with the lever.

9. A scraper including a frame, a bowl pivotally mounted thereon, an adjustable lever, a pin projecting from the bowl parallel to and ahead of its pivotal connection with the frame, an arm normally projecting under and engaging the pin, a shaft turnably mounted in the frame and on which said arm is fixed, another arm projecting from and affixed to said shaft, a link ex-

tending from said other arm, releasable catch means between the link and lever normally holding the two in driving engagement, a trip structure operable at will for releasing the link from the lever, whereby the arm is then free to be turned by the pressure of the pin thereagainst to enable said pin to pass by the arm, and spring means acting on said arm to restore the arm to its normal position.

10. A structure as in claim 9, in which additional spring means acts on the link to then cause said link to resume its driving engagement with the lever.

11. A scraper including a pivotally mounted bowl, stop pins on the bowl, a shaft turnable adjacent the bowl, means normally preventing rotation of the shaft, arms on the shaft normally engaging the stops to prevent rotation of the bowl, and means to release the shaft to allow it to rotate, whereupon with the forward movement of the bowl the stop pins will act against the arms to rotate the shaft and carry the arms out of engagement with the stop pins and allow the bowl to rotate.

12. A scraper including a pivotally mounted bowl, stop pins on the bowl, a shaft turnable adjacent the bowl, means normally preventing rotation of the shaft, arms on the shaft normally engaging the stops to prevent rotation of the bowl, means to release the shaft to allow it to rotate, whereupon with the forward movement of the bowl the stop pins will act against the arms to rotate the shaft and carry the arms out of engagement with the stop pins and allow the bowl to rotate, and means to then return the shaft to normal position.

13. A scraper including a pivotally mounted bowl, stop pins on the bowl, a shaft turnable adjacent the bowl, means normally preventing rotation of the shaft, arms on the shaft normally engaging the stops to prevent rotation of the bowl, means to release the shaft to allow it to rotate, whereupon with the forward movement of the bowl the stop pins will act against the arms to rotate the shaft and carry the arms out of engagement with the stop pins and allow the bowl to rotate, and means to then return the shaft to normal position, such means including a projecting arm on the shaft and a yieldable element interposed between the arm and the scraper frame.

In testimony whereof I affix my signature.
